(57) **CLAIM**

The ornamental design for a support structure for free standing canopy, as shown and described.

DESCRIPTION

FIG. 1 is a perspective view of a support structure for free standing canopy according to the design; FIG. 2 is a front elevation view thereof; FIG. 3 is a back elevation view thereof; FIG. 4 is a right side elevation view thereof; FIG. 5 is a left side elevation view thereof; FIG. 6 is a top plan view thereof; and, FIG. 7 is a bottom plan view thereof. Broken lines are environmental only and form no part of the claimed design.

1 Claim, 7 Drawing Sheets
